[57] CLAIM

The ornamental design for the multiple-contact electrical connector, as shown and described.

DESCRIPTION

FIG. 1 is a perspective view of an electrical connector embodying the design;

FIG. 2 is a top plan view thereof;

FIG. 3 is a front elevation thereof;

FIG. 4 is a side elevation thereof;

FIG. 5 is a rear elevation thereof; and,

FIG. 6 is a bottom plan view thereof.

The side opposite FIG. 4 is a mirror image of that figure.
